WEFT REPLENISHING LOOM OPERATING WITH TWO SHUTTLES

Richard G. Turner, Worcester, Mass., assignor to
Crompton & Knowles Loom Works, Worcester,
Mass., a corporation of Massachusetts

Application March 20, 1948, Serial No. 16,064

19 Claims. (Cl. 139—232)

1

This invention relates to improvements in bobbin changing looms operating with two shuttles which run pick and pick during part at least of the time the loom is in operation.

In certain fabrics it is desirable to have single picks of one type of weft followed by single picks of a different type. As a sample of such a fabric mention may be made of crepe in which single picks of a right hand twist weft alternate with single picks of a left hand twist weft. At the present time it is necessary to produce such fabrics on non-automatic looms because no simple and efficient automatic loom is available for weaving them. It is the general purpose of the present invention to provide a bobbin changing loom having a two-stack magazine at one end thereof for the replenishment of two shuttles which can run pick and pick.

The shuttles may run pick and pick throughout loom operation, or pick and pick weaving may be interrupted to weave a band of several successive picks of one type of weft. This band may alternate either with another band of the other type of weft, or with pick and pick weaving. The interruption of pick and pick weaving can occur either between replenishment of one shuttle and detection of weft in the other shuttle, or between indication of exhaustion by one shuttle and its replenishment. In either event a delay of at least two picks will occur between indication and transfer. It is another object of the present invention to provide a weft detecting system to indicate weft exhaustion on a pick when the empty shuttle is inactive, and replenish the shuttle on the next pick it is inactive whether or not there has been an interruption of pick and pick weaving. The indication will be stored in a holding contact, and a second contact closed at a later time by the pattern chain will complete a circuit closure of which causes replenishment.

When pick and pick looms operate with but two shuttles and weft detection for both of them occur at the same side of the loom it is found that one shuttle can give usable indications of weft exhaustion on even numbered picks only of the loom while the other shuttle can give usable indications on odd numbered picks only. In order that the replenishing operation may be initiated or completed on either even or odd numbered picks of the loom it is a further object of the invention to operate those parts of the loom associated with the replenishing operation by mechanism operating on one-pick time. In the description set forth hereinafter I show the well-known Knowles head pattern mechanism for this purpose, but I do not wish necessarily to be limited in the practice of my invention to a head motion.

In the usual multicolor bobbin changing loom the selector which determines from which stack

2

a bobbin shall be transferred moves in time with the shifting shuttle boxes at the end of the loom opposite the magazine. In a two-shuttle pick and pick loom, however, these boxes shift at a time when it is desirable to select the bobbin to be transferred and it is not feasible to control the selector from the shuttle boxes, or the pattern chain rolls or indicators which control the boxes. It is a still further object of the invention to utilize a part of the pattern mechanism independent of the shuttle boxes and their indicators to position the selector.

A loom of the type set forth herein may have either home boxes for the two shuttles at the end of the loom opposite the magazine, or the shuttles may each enter both the top and the bottom shuttle boxes. In the first condition it is desirable to have a weft detector for each shuttle as shown in the preferred form of the invention set forth hereinafter, but under these conditions indication of weft exhaustion could be given on successive picks if both shuttles were depleted of weft. It is a further object of the invention to nullify one of these successive indications of weft exhaustion during part of the loom cycle so that it will not interfere with the other indication, and nullify the other indication during another part of the loom cycle so that it cannot interfere with said one indication. This nullification can conveniently be effected by the chain control for the selector.

When the shuttles do not have home boxes it is possible to use a single detector and manipulate the shuttles in such manner that first one shuttle enters the box corresponding to the weft detector and then the other shuttle, thereby permitting detection of both shuttles by one feeler mechanism. This type of detection is set forth in the first modification of the invention.

With these and other objects in view which will appear as the description proceeds, my invention resides in the combination and arrangement of parts hereinafter described and set forth.

In the accompanying drawings, where three forms of the invention are set forth,

Fig. 1 is a front elevation of a loom partly in section having the preferred form of the invention applied thereto,

Fig. 2 is an enlarged end elevation partly in section looking in the direction of arrow 2, Fig. 1,

Fig. 3 is a diagrammatic plan view of the vibrator lever means of the head mechanism which operate the shuttle boxes and certain parts of the weft replenishing mechanism.

Fig. 4 is a diagrammatic view showing the relative positions of the shuttles and the shuttle boxes for the preferred eight-pick cycle of operation of the loom,

Fig. 5 is a diagrammatic view setting forth the

electric circuits used with the preferred form of the invention.

Fig. 6 is a diagram showing a draft of the pattern chain used with the preferred form of the invention.

Fig. 7 is an enlarged detail partly in section of the structure shown at the lower right hand part of Fig. 2.

Fig. 8 is a detailed elevation looking in the direction of arrow 8, Fig. 1.

Fig. 9 is a diagrammatic view looking in the direction of arrow 9, Fig. 3, and showing that part of the head mechanism which closes the aforesaid second contact of the detector circuit.

Fig. 10 is a view similar to Fig. 4 but shows an eight-pick cycle for the loom operating according to the first modified form of the invention.

Fig. 11 is a diagrammatic view showing the electric circuits for a single weft detector as employed in the first modified form of the invention.

Fig. 12 is a diagram of the draft of the pattern chain used with the cycle shown in Fig. 10, and

Fig. 13 shows a draft of a pattern chain used with the second modification of the invention and also indicates the order of picking the shuttles when pick and pick weaving is interrupted by plain bands of successive similar picks.

Referring particularly to Figs. 1 and 2, the loom frame 19 supports a lay 11 driven by the top or crank shaft 12 of the loom which reciprocates the lay once for each pick of the loom. A gear 13 secured to shaft 12 meshes with a second gear 14 of twice its size secured to the bottom shaft 15 which rotates once in two picks of the loom.

Each end of the lay is provided with shifting shuttle boxes, the gangs of boxes at the right and left ends being designated, respectively, at RG and LG. The gang RG is actually made with three cells only two of which, however, are utilized by the shuttles. The top box or cell 16 is the box in which replenishment occurs and immediately below it in what ordinarily would be the second cell is a deflector or baffle 17 which directs an ejected bobbin forwardly, or to the left as viewed in Fig. 2. The bottom box or cell 18 will be in active position when the top cell 16 is in high or transfer position.

The gang LG has top and bottom boxes or cells 20 and 21 associated with over and under electric feelers or weft detectors F1 and F2, respectively, secured to the lay in such position that when gang LG is up a shuttle in top cell 20 will have its weft detected by feeler F1, but when the gang LG is down a shuttle in the bottom cell or box 21 will have its weft detected by feeler F2. Picker sticks 22 are shown as part of the picking mechanism used in the loom, and these sticks will ordinarily operate each pick of the loom so that any shuttle in active position will be picked.

The pattern chain controlled mechanism K is of the well-known Knowles head type and comprises top and bottom mutilated gear cylinders 25 and 26, respectively, which rotate continuously during loom operation in the direction indicated by the arrows in Fig. 1, each cylinder completing a rotation each pick of the loom. The cylinders 25 and 26 may be considered the operating means for certain of the structure to be described. The driving means for these cylinders is not shown, but they rotate once for each pick of the loom to operate vibrator lever means which

will be described in more detail hereinafter. The head mechanism K is provided with a pattern chain C for determining the vertical positions of the vibrator levers. The chain is on one-pick time and presents a new bar to controlling position over chain cylinder 28 each pick of the loom.

Gang LG is supported by a box lifter rod 30 attached to a flexible connector 31, such as a chain, trained over lay carried sheaves 32 and then down around a loom frame supported sheave 33, thence upwardly over a sheave 34 and around a stationary sheave 35 mounted as indicated in Fig. 8 to a box lifter lever 36. The lower end of lever 36 moves about a stationary pivot 37 and its upper end is attached to a vibrator connector 38 pivoted to a vibrator gear 39 rotatably mounted on a vibrator lever 40. The latter is pivoted on a heel pin 41 formed as part of the mechanism K.

The pattern chain C has a row of high and low indicators 43 and 44, respectively, as indicated in column HS of Fig. 6. These indicators 43 and 44 alternate in the preferred form of the invention so that vibrator lever 40 is up on one pick and down on the next, thereby causing the vibrator gear 39 to be turned first in one direction by one of the mutilated cylinders 25-26 on one pick and then in the opposite direction by the other mutilated cylinder on the next pick. In this way the gang LG is shifted each pick of the loom so that first the top cell 20 and then the bottom cell 21 is active.

The gang RG is mounted on the box lifter rod 50 connected to a flexible chain 51 trained over lay carried sheaves 52 and 53 and then down around a sheave 54 concentric with sheave 33 and thence up over a sheave 55 concentric with sheave 34. Both sheaves 34 and 55 rotate on a stationary axis 56 supported by the head mechanism K. Chain 51 is trained around a sheave 57 rotatable on the lower end of a box lifter lever 58 pivoted on fixed stud 59. Chain 51 extends to the left, Fig. 1, from sheave 57 and is anchored at 60 to a stationary part of the loom. This anchoring of chain 51 represents a departure from the usual construction of mechanism K.

The upper end of lever 58 is pivoted to a vibrator connector 61 pivoted to a vibrator gear 62 mounted on a vibrator lever 63 which is over the high and low indicators 64 and 65, respectively, of the pattern chain, see column MD, Fig. 6. This vibrator lever 63 and the sheave 57 control the vertical position of gang RG, and when sheave 57 is to the left of axis 59 as shown in Fig. 1 gang RG will be down with box 16 active, but when vibrator gear 62 is turned by cylinder 25 due to arrival of a high roll indicator 64 under vibrator lever 63 sheave 57 will move to the right of the position shown in Fig. 1 and gang RG will move to its high position to make box or cell 18 active and place cell 16 in high or transfer position.

The head mechanism K has only two vibrator levers assigned to the shuttle boxes, but when supplied for pick and pick work this mechanism is ordinarily provided with two additional vibrator levers and it is also common practice where necessary to use still other levers to be operated by the chain C. The replenishing mechanism about to be described is either controlled or operated by these additional levers.

The magazine M in back center position is provided with front and back stacks of reserve bobbins B1 and B2, respectively, and is mounted for rocking movement about a stationary pivot

70, see Fig. 2 in a manner shown in my prior patent No. 2,128,974. The upper end of the magazine is connected to a rod 71 extending rearwardly to a bell crank lever 72 pivoted on the loom as at 73. A selector 74 depends from lever 72 and has the lower end thereof provided with a hook 75 the back and forth position of which is determined by a selector lever 76 moving about a stationary axis 77. The hook is slidable through lever 76 and a spring 78 normally tends to move the upper part of the selector lever forwardly, or to the left as viewed in Fig. 2, to move the hook 75 to its front position. Lever 76 can, however, be rocked in a clockwise direction as viewed in Fig. 2 to move the hook 75 to its rear position.

The head mechanism K is provided with a third vibrator lever 80 for the selector carrying a vibrator gear 81 attached to a connector 82 operatively connected to the upper end of a lever 83 pivoted at 59. Lever 83 is connected to a chain 84 or other similar flexible connector which is guided over sheave 85 at the magazine end and extends downwardly and is attached to arm 86 of the selector lever 76. Vibrator lever 80 is controlled by high and low rolls 87 and 88, respectively, of the pattern chain C appearing in vertical column HD, Fig. 6.

A fourth vibrator lever 95 in the head mechanism K is provided with a vibrator gear 96 and a connector 97 attached to a lever 98 moving about axis 37. Lever 98 is attached to a flexible connector or chain 99 which is guided over sheaves 100 and 101 at the magazine end of the loom and is connected to the forward arm 102 of a magazine positioning or control lever 103 moving about a fixed pivot 104. A spring 105 normally tends to hold lever arm 102 in down position as shown in Fig. 2, but permits upward movement thereof. An operating pin or actuator 106 is secured to the rear arm 107 of lever 103 and is provided for operation or depression of hook 75 when the latter is registered with it on replenishing beats of the loom.

An electric switch lever 110 is pivoted on the heel pin 41 and extends over high and low rolls 111 and 112, respectively, of the pattern chain, see column SL, Fig. 6. Mounted on the head mechanism K over lever 110 is an electric switch 114 which is open when lever 110 is down but is closed when the lever is raised by a high roll 111.

The electric circuit used with the preferred form of the invention is shown in Fig. 5, wherein one of the detector prongs 115 of each of the feelers F1 and F2 is grounded as at 116. Feeler F1 is connected to contact 117 of a switch 118, while the other feeler F2 is connected to a second contact 119 of switch 118. Switch 118, omitted from Fig. 1 but supported by head K over vibrator lever 80, see Fig. 3, is connected to an initiating coil 120 provided with an armature or holding contact 121 normally held down by a spring 122 out of engagement with a stationary contact 123. When the armature is attracted by energization of the initiating coil 120 it engages the contact 123 and is held in engagement therewith upon deenergization of the initiating coil by a hook 124 normally held to the left by a spring 125. Hook 124 is on an armature 126 of a releasing coil 127 normally deenergized.

Located over the normally down vibrator lever 95 and mounted on the head mechanism K is a solenoid 130 normally deenergized but effective when energized to lift vibrator lever 95. Low rolls or indicators 131 shown in vertical column

MS of the pattern chain C, Fig. 6, permit the vibrator lever 95 to be ordinarily in low position.

A source of electric power P, which may be a transformer, is in an energizing circuit including the holding contact and switch 114 in series and also the solenoid. When the holding contact 121 is held up against contact 123 and switch 114 is closed solenoid 130 will be energized.

10 The preferred form of the invention operates in an eight-pick cycle indicated in Fig. 4, wherein the positions of the shuttle boxes and shuttles for the eight picks are designated at I-VIII. The shuttle box positions shown in Fig. 4 are those existing when the lay is on top center and picking is about to occur at the start of a one pick cycle. The horizontal rows I-VIII of indicators in Fig. 6 are those which produce the correspondingly numbered shuttle box positions I-VIII shown in Fig. 4.

In explaining the operation of the preferred form of the invention it will be assumed that the two shuttles S1 and S2 are both depleted of weft and have bobbins provided with metallic ferrules which are uncovered upon exhaustion of weft to connect electrically the prongs of the corresponding weft detector or feeler when the shuttles are in detecting position.

On the first pick of the sequence shown in position I, the lay being on top center at the beginning of this first pick, shuttle S1 is in cell 20 of gang LG and the prongs 115 of feeler F1 will be electrically connected to cause feeler F1 to indicate weft exhaustion. Shuttle S2 is in box cell 16 and is about to be picked toward cell 21 of gang LG. Because of the fact that a low roll 88 is under vibrator lever 80 switch 118 will be in the full line position shown in Fig. 5 corresponding to feeler F1, and selector lever 76 will place hook 75 under or in register with actuator pin 106. Indication of weft exhaustion by feeler F1 will therefore complete a circuit through the initiating coil 120 and contact 123 will be engaged by the armature or holding contact 121. On this pick, however, switch 114 is open due to the fact that a low roll 112 is under switch lever 110.

At the bottom center following position I shuttle S2 will be boxed in cell 21 and gang LG will start to move down. Even though shuttle S1 moves away from feeler F1, the holding contact 121 will remain closed because of the action of hook 124.

In position II shuttle S1 is picked toward cell 16 of gang RG and at the bottom center following position II gang RG will start up and will be in high position so that box 16 will be in transfer position relatively to the magazine M at the next back center position of the lay following position III.

60 In considering Figs. 4 and 6 it should be borne in mind that the horizontal rows I-VIII of Fig. 6 show the indicators which produce the correspondingly numbered shuttle and shuttle box positions I-VIII of Fig. 4. In order to produce these latter positions, however, the chain indicators must be in their indicating positions under their levers not later than the preceding bottom center positions of the lay in order to allow the vibrator lever means to complete box shifting by top center. Also, a high roll 111 will be moving up on cylinder 28 during the latter part of the first pick just prior to position II, and will be moving under lever 110 not long after position II during the second pick, as indicated by the dotted line circle 111a in column SL, Fig. 6, to

lift lever 110. High roll 111 will complete raising of lever 110 to close switch 114 in time to energize solenoid 130 and lift vibrator lever 95 so that at the next bottom center position, occurring in the second pick, lever 95 will start to move pin 106 due to action of top cylinder gear 25 and when the shuttle boxes reach position III actuator pin will have been moved down to depress hook 75 to rock magazine M to place the lowest bobbin B1 in transfer position.

When pin 106 moves down, the forward arm 102 of lever 103 rises and lifts a rod 135 connected thereto to raise a positioning member 136 pivoted to 137 to elevate the transerrer latch 138 into the path of a bunter 139 secured to and extending rearwardly from the lay. These operations are completed with the lay moving rearwardly and in top center position III.

As the lay approaches back center the bunter 139 will engage the latch and rock the transerrer arm 140 to transfer the lowest bobbin B1 into shuttle S1 and transfer will be completed at back center. As the lay moves forwardly bunter 139 will release the latch 138 but arm 102 of lever 103 will still be up. Chain C will however move a low roll 112 under lever 110 and the latter will fall to open switch 114 in time to allow vibrator lever 95 to fall due to deenergization of solenoid 130 so that vibrator gear 96 can be engaged by bottom gear cylinder 26 at or about bottom center. As vibrator connector 97 moves to the right, Fig. 1, spring 105 will be able to rock lever 103 counter-clockwise, Fig. 2, back to its normal position and the accompanying descent of rod 135 will allow the transfer latch to fall to its normal non-transfer position, Fig. 2. The up movement of pin 106 occurring at this time allows the magazine M to be returned to its normal position against stop 141 by spring 142, and the magazine will be reset at position IV, Fig. 4.

It is necessary to open the holding contact 121 to enable shuttle S2 to be replenished during the second four pick sequence, and this is accomplished by upward movement of arm 107 of lever 103 as pin 106 rises.

A normally open switch 150, see Fig. 7, is mounted on a stationary part of the loom and has an operating arm 151 on which a trip finger 152 is pivoted as at 153 to be in the path of a trip pin 154 on arm 107 behind pin 106. When the operating pin 106 has its working or down stroke as already described trip pin 154 will turn finger 152 on its pivot without moving arm 151, see dotted lines Fig. 7, but on the upward or return stroke of arm 107 pin 154 will engage finger 152 and lift arm 151 to close switch 150, see dot and dash lines, Fig. 7.

Closure of switch 150 will energize releasing coil 127, as will be apparent from Fig. 5, and hook 124 will move from under holding contact 121 to permit the latter to be moved down to its open position by spring 122. As arm 107 of lever 103 approaches its normal or high position it releases finger 152 and switch 150 opens. The electric circuits are now back to their normal or inactive condition.

The reason for using the finger 152 on arm 151 is to permit the solenoid to be energized throughout the time vibrator gear 96 is being turned by upper cylinder 25 of mechanism K. Releasing coil 127 could probably be energized at the end of the down or working stroke of pin 106 without much likelihood that gear 96 would start to fall before the working stroke is actually completed,

but I prefer to open the holding circuit on the solenoid at a later time.

All the parts are now back to their normal position and the first four-pick sequence is completed. It will be noted that although shuttle S2 is detected by feeler F2 in position II, Fig. 4, this latter feeler cannot indicate exhaustion because switch 118 is out of engagement with contact 119, and indication of weft exhaustion can 10 therefore be given by feeler F1 only during the first four-pick sequence.

At the beginning of the second four-pick sequence, which starts with position V, a high roll 87 will raise vibrator lever 80 so that the top gear cylinder 25 will turn vibrator gear 81 in a counter-clockwise direction as viewed in Fig. 1 to move connector 82 to the left. This results in rocking the selector lever 76 in a clockwise direction as viewed in Fig. 2 to move hook 75 rearwardly, to the right Fig. 2, out of register with the operating pin 106. The latter will therefore have an idle down motion and the magazine will remain in its normal position. At this time switch 118 is also changed to the dotted line position shown in 20 Fig. 5, thereby enabling feeler F2 to indicate exhaustion of weft.

During the second four-pick sequence the gang RG will shift in an order the reverse of its shifting for the first four-pick sequence, that is, the gang RG will be up in positions V, VI and VIII, and will be down in position VII to enable shuttle S2 to be picked into box cell 16.

Since shuttle S2 is assumed to be depleted of weft feeler F2 will indicate weft exhaustion on 35 the sixth pick, position VI, and the replenishing operation which follows will be similar to that described for shuttle S1. A second high roll 111 will effect closure of switch 114 to close the solenoid circuit as already described for shuttle S1. During this second four-pick sequence shuttle S1 is in detecting position with respect to feeler F1 on the fifth pick, but it cannot indicate because switch 118 has moved away from contact 40 117. The second four-pick sequence ends with replenishment of shuttle S2 in position VIII, and a second eight-pick cycle starts.

It will be noted that indication in the first four-pick sequence is initiated on an odd numbered pick of the eight-pick cycle, that is, the first pick, and replenishment is completed on another odd pick as suggested by bobbin B1 in position III, but during the second four-pick sequence indication of weft exhaustion occurs on an even numbered pick, that is, the sixth pick and replenishment is completed on another even numbered pick as suggested by bobbin B2 in position VIII. These operations can occur on odd and even numbered picks of the cycle because of the fact that the head mechanism K operates on one-pick time.

The head mechanism K usually operates with a lock knife 157, Fig. 1, which is in locking position with respect to the vibrator levers from bottom center to top center, and then moves out to non-locking position, or to the right as viewed in Fig. 1, from top center through back center to bottom center to allow the vibrator levers to move vertically if called upon to do so by the pattern chain 28. In order that energization of the solenoid 130 may be delayed until after the lock knife has moved to its unlocking position the lever 110 has a shoe 160 for engaging with the indicators in vertical column SL shown in Fig. 6. This shoe is somewhat off center with respect to the axis of the cylinder 28, see Fig. 9, to delay closure of 70 switch 114 until the lock knife moves to unlocked

position to permit vibrator lever 95 to rise freely to its high position upon energization of the solenoid. Shoe 160 will hold lever 110 up and switch 114 closed to keep solenoid 130 energized until bottom center, at which time the lock knife locks lever 95 up and its motion to move pin 106 is started by the top gear cylinder 25.

In the first modified form of the invention the greater part of the structure already described is used, but there will be only one feeler F3 which will be in the position of feeler F1 of the preferred form. Also, since but one weft detector will be used it will be necessary to alter the order of shifting of gang LG. As seen in Fig. 10, gang LG will not shift every pick of the loom as in the preferred form, but will be down for one pick only during the first four-pick sequence and will be up for one pick only during the second four-pick sequence. This order of shifting allows both of the shuttles S1 and S2, which may be the same as with the preferred form, to be detected by the single feeler F3, and is controlled by high and low chain indicators 161 and 162, respectively, in column HS' of chain C1, see Fig. 12.

Since there is only one feeler in the first modified form of the invention the switch 118 will be omitted and the right side or electrode of feeler F3 as shown in Fig. 11 will be connected directly to the initiating coil 120. Otherwise the circuit of the modified form will be the same as that used for the preferred form, and the indications of weft exhaustion and the replenishments will be the same as in the preferred form.

In both Figures 6 and 12 the dotted large circles 163 shown for positions III and VIII suggest the raised position of vibrator lever 95 due to energization of the solenoid. There are no high rolls in column MS in either Fig. 6 or Fig. 12 so that vibrator lever 95 will always be normally down except when raised by the solenoid. In Figs. 4 and 10 the order of shifting of the gang RG will be the same and will enable each of the two shuttles to enter the top box cell 16 during an eight-pick cycle. The horizontal rows of indicators in Fig. 12 are indicated at I'-VIII' similarly to the corresponding positions in Fig. 10. In this modified form indication of weft exhaustion and replenishment occur on odd picks of the first four-pick sequence and on even picks in the second four-pick sequence, as in the preferred form.

In the foregoing description it has been assumed that the fabric being woven is pick and pick throughout, but certain features of the invention are not limited to the weaving of such a fabric. It may be desirable, for instance, to have bands of pick and pick fabric alternate with bands formed by a plurality of picks of the same kind of weft, in which case there will be interruptions in the pick and pick cycle such as shown in Fig. 13, which sets forth the second modification of the invention.

Fig. 13 shows a sequence of twelve picks eight of which are similar to the picks represented in Fig. 6, and four of which represent two interruptions of two successive similar picks each. The weaving of pick and pick can be interrupted either immediately after a transfer has been completed, in which event it will not interfere with a normal replenishing operation, or it can occur between indication of weft exhaustion and the ensuing transfer. This second modification operates with shuttles S5 and S6 corresponding to shuttles S1 and S2, respectively, of the pre-

ferred form of the invention, and will employ two feelers similar to feelers F1 and F2. Interruptions could occur in the sequence shown in Fig. 10, but it is not thought necessary to show interruption for the first modification. The first type of interruption already mentioned occurs after replenishment of shuttle S5 while the second type of interruption occurs immediately after a replenishing operation has been initiated by shuttle S6.

Shuttle S5 will be replenished in the first three picks I'-III', as already described for the replenishment of shuttle S1. The first interruption occurs on picks IV'' and V'' when shuttle S6 is kept in action by high and low indicators the same as for pick III''. This will result in the laying of three picks from shuttle S6, the first of which, however, should be considered as part of the preceding pick and pick weaving.

Pick VI'' corresponds to pick IV of Fig. 6, and similarly picks VII'' and VIII'' correspond to picks V and VI of Fig. 6. On the eighth pick shuttle S6 will indicate weft exhaustion while shuttle S5 is active, but there will be a second interruption on the next two picks IX'' and X'' during which shuttle S5 remains active. The chain C2 will have the same indications for these last two picks as for pick VIII'', that is, there will be low rolls 112 for these picks to prevent closure of switch 114. Pick and pick weaving is then resumed on pick XI'' and replenishment of shuttle S6 will occur on pick XII'' due to a high roll 111.

Although each of the interruptions has been described as involving only two picks, a greater number of picks could be woven for each interruption, and closure of the holding circuit will be delayed during any interruption occurring between indication of weft exhaustion and the transfer called thereby.

From the foregoing it will be seen that I have provided means by which each of two shuttles carrying distinctive weft running pick and pick can be replenished by bobbins drawn from a single magazine located at one end of the loom. A holding contact or switch is closed upon indication of weft exhaustion by the weft detecting mechanism, but the holding circuit for the solenoid is not closed by pattern chain controlled switch 114 until the next pick, whereupon the indication is completed. It is because of this manner of closing switch 114 that a lapse of at least two picks can occur between indication of weft exhaustion by the weft detecting mechanism and bobbin transfer. Bobbins are transferred when the lay is on back center position and top cell 116 of gang RG is up in transfer position and at rest relatively to the lay. Furthermore, the selector lever 76 is rocked under control of the pattern chain independently of the shifting of the gang LG or the chain indicators controlling it. When two feelers are used switch 118 is in one position in the first four-pick sequence to enable only one of the feelers to indicate weft exhaustion and is in another position during the second four-pick sequence to enable the other feeler only to indicate. In all forms of the invention the gang RG shifts in such order that each of the two shuttles can enter the top cell 16 and be moved to high or transfer position relatively to the magazine. The releasing coil 127 is energized preferably on the return stroke of lever arm 107. In the second modification the detecting and transferring operations occur the same as in the eight-pick cycles, except that

when an interruption occurs to lay successive similar picks bobbin transfer may be delayed. The fact that the head mechanism K operates on one pick enables detection of weft and transfer to occur on either even or odd numbered picks of the loom cycle. Each vibrator lever, gear and connector may be considered collectively as a vibrator lever means.

Another application, Serial No. 16,065, filed March 20, 1948, shows some of the structure set forth herein, but that application is directed to a shuttle changing loom, whereas the present application relates to a bobbin changing loom.

Having thus described my invention it will be seen that changes and modifications may be made therein by those skilled in the art without departing from the spirit and scope of the invention and I do not wish to be limited to the details herein disclosed, but what I claim is:

1. In a bobbin changing loom having two shuttles running pick and pick, a magazine at one end of the loom having two groups of reserve bobbins corresponding to the shuttles and being normally in one position corresponding to one of said shuttles to locate the lowest bobbin in one group for transfer but movable to another position corresponding to the other shuttle to locate the lowest bobbin in the other group for transfer, shuttle boxes at the other end of the loom shifting to move each shuttle one at a time to inactive position for one pick, weft detecting mechanism at said other end of the loom to detect each shuttle at a time when the latter is in inactive position, an actuator for moving the magazine, a selector operatively connected to the magazine for moving the latter from said one position to said other position thereof, said selector being normally in one position in register with the actuator corresponding to said one shuttle and movable out of register with the actuator to another position corresponding to the other shuttle, pattern chain controlled vibrator lever means effective during the second pick after either shuttle when inactive is detected by the weft detecting mechanism to locate the selector in the position thereof corresponding to the detected shuttle, and other vibrator lever means effective on said second pick, provided indication of weft exhaustion was given by said detecting mechanism when detecting said inactive shuttle, to operate said actuator and cause the latter to move said selector if the latter is in register with the actuator to move the magazine to said other position thereof.

2. In a bobbin changing loom having two shuttles running pick and pick, a magazine at one end of the loom having two groups of reserve bobbins corresponding to the shuttles, said magazine being rockable to one or the other of two positions to place the lowest bobbin in either group in transfer position, shuttle boxes at the other end of the loom shifting to move each shuttle one at a time to inactive position for one pick, weft detecting mechanism at said other end of the loom to detect the weft of either shuttle at a time when the latter is inactive, an actuator for moving the magazine, a selector operatively connected to the magazine, pattern chain controlled vibrator lever means effective on the second pick following detection of one of said shuttles to cause the selector to register with the actuator and effective on the second pick following detection of the other shuttle to move the selector out of register with the actuator, and other vibrator lever means causing said actuator

to move on the second pick following detection of either shuttle, provided the latter has caused the weft detecting mechanism to indicate weft exhaustion, to move the selector to rock the magazine, provided the selector is in register with said actuator.

3. In a bobbin changing loom operating in an eight pick cycle comprising two successive four pick sequences, the loom having two shuttles with different wefts running pick and pick and having shifting shuttle boxes at each end thereof, a movable magazine at one end of the loom having two groups of reserve bobbins, one group for each shuttle, said magazine being normally in one position to place the lowest bobbin in one of said groups in transfer position but movable to another position to place the lowest bobbin in the other group in transfer position, pattern mechanism including four vibrator lever means one of which effects shifting of the shuttle boxes at said other end of the loom to move each shuttle to inactive position twice during the eight pick cycle, weft detecting means effective to indicate weft exhaustion in one shuttle only during the first four pick sequence when said one shuttle is inactive and effective to indicate weft exhaustion in the other shuttle only during the second four pick sequence when said other shuttle is inactive, the second vibrator lever means effective to raise the shuttle boxes at said one end of the loom on the second pick following detection of weft by said detecting mechanism in either four pick sequence, an actuator to move the magazine, a selector for operation by said actuator operatively connected to the magazine and normally in one position in register with the actuator but movable to another position out of register with the actuator, means maintaining the selector in said one position thereof during the second pick following detection of weft in the first four pick sequence and the third vibrator lever means placing the selector in the other position thereof during the second pick following detection of weft in the second four pick sequence, and the fourth vibrator lever means operating said actuator on the second pick following detection of weft in either four pick sequence, provided the weft detector indicates weft exhaustion, to move said selector if the latter is in register with the actuator to cause the magazine to move to said other position thereof.

4. In a bobbin changing loom operating in an eight pick cycle comprising two successive four pick sequences, the loom having two shuttles with different wefts running pick and pick and having shifting shuttle boxes at each end thereof, a movable magazine at one end of the loom having two groups of reserve bobbins, one group for each shuttle, said magazine being normally in one position to place the lowest bobbin in one of said groups in transfer position but movable to another position to place the lowest bobbin in the other group in transfer position, weft detecting mechanism at the other end of the loom effective to indicate weft exhaustion in one shuttle only during the first sequence and effective to indicate weft exhaustion in the other shuttle only during the second sequence, pattern mechanism including three vibrator lever means one of which effects movement of the shuttle boxes at said one side of the loom to move the top shuttle box thereof to transfer position relatively to the magazine on the second pick following detection of weft in either sequence, actuator mechanism to move the magazine, a selector

operatively connected to the magazine, the second vibrator lever means causing the selector to be out of register with the actuator means in one of said sequences and in a position corresponding to said one position of the magazine and in another position in register with the actuator mechanism in the other sequence and corresponding to the other position of the magazine, and means including the third vibrator lever means causing operation of said actuator mechanism on the second pick following indication of weft exhaustion, provided the weft detecting mechanism indicates weft exhaustion, to move the selector if the latter is in said other position thereof to move the magazine to the other position thereof.

5. In a bobbin changing loom operating in an eight pick cycle comprising two successive four pick sequences, the loom having two shuttles running pick and pick, the first shuttle having weft differing from the weft of the second shuttle, the loom having shifting shuttle boxes at each end thereof, a movable magazine at one end of the loom having two groups of reserve bobbins, one group for the first shuttle and the other group for the second shuttle, said magazine being normally in one position to place the lowest bobbin in one group in transfer position but movable to another position to place the lowest bobbin in another group in transfer position, weft detecting mechanism at the other end of the loom effective to detect weft on the first and sixth picks only of said cycle in the first and second shuttles, respectively, actuator mechanism to move the magazine to said other position thereof, selector mechanism operatively connected to the magazine and movable into and out of register with the actuator mechanism, means causing the selector to be in register with the actuator mechanism on the third pick of the cycle and out of register with the actuator mechanism on the eighth pick of the cycle, and means causing operation of the actuator mechanism on the third pick of the cycle if the first shuttle indicates weft exhaustion and on the eighth pick of the cycle if the second shuttle indicates weft exhaustion, the actuator mechanism and selector cooperating to move the magazine to said other position thereof if the selector is in register with the actuator mechanism.

6. In a bobbin changing loom operating in an eight pick cycle comprising two successive four pick sequences, the loom having two shuttles with different wefts running pick and pick and having shifting shuttle boxes at each end thereof, a movable magazine at one end of the loom having two groups of reserve bobbins, one group for each shuttle, said magazine being normally in one position to place the lowest bobbin in one of said groups in transfer position but movable to another position to place the lowest bobbin in the other group in transfer position, weft detecting mechanism effective to indicate weft exhaustion in the first shuttle on the first pick only of the cycle and effective to indicate weft exhaustion in the second shuttle on the sixth pick only of the cycle, provided the shuttles are depleted of weft, and means effecting replenishment of the first shuttle by a bobbin drawn from one of said groups on the third pick of the cycle if said first shuttle indicates weft exhaustion on the first pick of the cycle and effecting replenishment of the second shuttle by a bobbin drawn from the other group on the eighth pick of the

cycle if said second shuttle indicates weft exhaustion on the sixth pick of said cycle.

7. In a bobbin changing loom operating in an eight pick cycle and having two shuttles with different wefts running pick and pick, a movable magazine at one end of the loom having two groups of reserve bobbins, one group for each shuttle, weft detecting mechanism at the other end of the loom effective to indicate weft exhaustion in the first shuttle if the latter is depleted of weft on the first pick only of the cycle and indicate weft exhaustion in the second shuttle if the latter is depleted of weft on the sixth pick only of the cycle, and means effecting replenishment of either shuttle by a bobbin drawn from the corresponding group two picks later in said cycle than the pick on which the detecting mechanism indicates weft exhaustion of a depleted shuttle.

8. In a bobbin changing loom operating in an eight pick cycle comprising two successive four pick sequences, the loom having two shuttles with different wefts running pick and pick, a magazine at one end of the loom having two groups of reserve bobbins, one group for each shuttle, and means effective on an odd numbered pick of one of said sequences if one of said shuttles is depleted of weft to effect replenishment of said one shuttle by a bobbin drawn from one of said groups and effective on an even numbered pick of the other sequence if the other shuttle is depleted of weft to effect replenishment of said other shuttle by a bobbin drawn from the other group.

9. In a bobbin changing loom having two shuttles running pick and pick and operating on a cycle of eight picks each of which starts when the lay is on top center, said eight pick cycle comprising two successive four pick sequences, a magazine having a group of bobbins for each shuttle, a transfer latch normally in non-transfer position, electric weft detecting means effective on an even numbered pick of one of said sequences to give indication of weft exhaustion if one of said shuttles is depleted of weft and effective on an odd numbered pick of the other sequence to give indication of weft exhaustion if the other shuttle is depleted of weft, a holding contact closed when the detector means gives indication of weft exhaustion and remaining closed after said indication, a second contact normally open, pattern chain mechanism effective to close said second contact before the lay reaches bottom center on the pick following indication of weft exhaustion by said detector means in either sequence, a solenoid, electric circuit means effecting energization of said solenoid when both contacts are closed, and vibrator lever means operating on one pick time caused by the solenoid when the latter is energized to move said latch to transfer position on the second pick following indication of weft exhaustion in either sequence.

10. In a bobbin changing loom having two shuttles running pick and pick and operating in a cycle of eight picks each of which starts when the lay is on top center, said eight pick cycle comprising two successive four pick sequences, a magazine having two groups of reserve bobbins, one group for each shuttle, a transfer latch normally in non-transfer position, a positioning member for the latch normally in non-transfer position, vibrator lever means normally in down position but effective when raised to move said positioning member and cause the latter to move the latch to transfer

position, electric weft detector means effective on an even numbered pick in one of said sequences to detect and give indication of weft exhaustion if one of said shuttles is depleted of weft and effective on an odd numbered pick in the other sequence to detect and give indication of weft exhaustion if the other shuttle is depleted of weft, a holding contact closed when the detector gives indication of weft exhaustion in either of said sequences and remaining closed after said indication, a second normally open contact, pattern chain mechanism effecting closure of said second contact before the lay reaches bottom center on the pick next following the pick on which indication of weft exhaustion is given, a solenoid, electric circuit means including said contacts and solenoid in series energizing the latter when both contacts are closed, and vibrator lever means effective incident to energization of said solenoid to move said latch to the transfer position thereof.

11. In a weft replenishing loom operating with two shuttles running pick and pick, one shuttle being inactive on even numbered picks of the loom and the other shuttle being inactive on odd numbered picks of the loom, weft detecting means to detect the weft of said one shuttle on picks which are even numbered and detect the weft of the other shuttle on picks which are odd numbered, a magazine at one end of the loom having two groups of reserve bobbins, and means causing replenishment of said one shuttle by a reserve bobbin from one of said groups on the next even numbered pick after indication of weft exhaustion of said one shuttle and causing replenishment of said other shuttle by a reserve bobbin from the other of said groups on the next odd numbered pick after indication of weft exhaustion of said other shuttle.

12. In a weft replenishing loom operating with two shuttles running pick and pick, one shuttle being inactive on even numbered picks of the loom and the other shuttle being inactive on odd numbered picks of the loom, weft detecting means to detect the weft of said one shuttle on picks which are even numbered and detect the weft of the other shuttle on picks which are odd numbered, a magazine at one end of the loom having two groups of reserve bobbins, and means causing replenishment of said one shuttle by a reserve bobbin from one of said groups on an even numbered pick occurring after indication of weft exhaustion of said one shuttle and causing replenishment of said other shuttle by a reserve bobbin from the other of said groups on an odd numbered pick occurring after indication of weft exhaustion of said other shuttle.

13. In a weft replenishing loom having two shuttles running pick and pick and operating on a cycle of eight picks each of which starts when the lay is on top center, a magazine at one end of the loom having two groups of reserve bobbins for replenishment of the shuttles, one group for each shuttle, a transfer latch for the magazine normally in non-transfer position but movable to transfer position preparatory to replenishment of either shuttle, electric weft detector means for the shuttles giving indication of weft exhaustion on the first pick of said cycle if one of said shuttles is depleted of weft and giving indication of weft exhaustion on the sixth pick of said cycle if the other shuttle is depleted of weft, an electric holding contact closed upon indication of weft exhaustion in either shuttle by the detector means and remaining closed after said indication, a sec-

ond electric contact normally open, pattern chain mechanism effecting closure of said second contact before the lay reaches bottom center on the pick next following the pick on which indication of weft exhaustion is given, a solenoid, electric circuit means including said contacts and solenoid in series energizing the latter when both contacts are closed, and vibrator lever means effective incident to energization of said solenoid to move said latch to the transfer position thereof.

14. In a weft replenishing loom having two shuttles running pick and pick and operating on a cycle of eight picks each of which starts when the lay is on top center, a magazine at one end of the loom having two groups of reserve bobbins for replenishment of the shuttles, one group for each shuttle, a transfer latch for the magazine normally in non-transfer position but movable to transfer position preparatory to replenishment of either shuttle, a control member for the latch normally in non-transfer position but movable to transfer position to place the latch in transfer position, vibrator lever means normally in down position but operative when in raised position to effect movement of the control member and latch to their respective transfer positions, the control member subsequently returning from transfer position to the non-transfer position thereof, electric weft detector means capable of indicating weft exhaustion in one shuttle on the first pick and in the other shuttle on the sixth pick of said cycle, an electric holding contact closed when the detector means indicates weft exhaustion in either shuttle and remaining closed after said indication, a second normally open electric contact, pattern chain mechanism effecting closure of said second contact before the lay reaches the bottom center position thereof on the next pick after indication by the detector means, a solenoid effective when energized to move said vibrator lever means to the raised position thereof, electric circuit means including said contacts and solenoid in series and effective to energize the solenoid when both contacts are closed, and means causing opening of said holding contact incident to movement of the control member to and from the transfer position thereof.

15. In a weft replenishing loom having two shuttles running pick and pick and operating on a cycle of eight picks each of which starts when the lay is on top center, a magazine at one end of the loom having two groups of reserve bobbins for replenishment of the shuttles, one group for each shuttle, a transfer latch for the magazine normally in non-transfer position but movable to transfer position preparatory to replenishment of either shuttle, a control member for the latch normally in non-transfer position but movable to transfer position to place the latch in transfer position, vibrator lever means normally in down position but operative when in raised position to effect movement of the control member and latch to their respective transfer positions, the control member subsequently returning from transfer position to the non-transfer position thereof, electric weft detector means capable of indicating weft exhaustion in one shuttle on the first pick and in the other shuttle on the sixth pick of said cycle, an electric holding contact closed when the detector indicates weft exhaustion in either shuttle and remaining closed after said indication, a second normally open electric contact, pattern chain mechanism effecting closure of said second contact before the lay reaches the bottom center position thereof on the next pick after indication

by the detector means and opening said second contact on the pick following said next pick, a solenoid effective when energized to move said vibrator lever means to the raised position thereof, electric circuit means including said contacts and solenoid in series effective to energize the solenoid when both contacts are closed, and means controlled by said control member when the latter returns from the transfer position to the non-transfer position thereof to effect opening of said holding contact.

16. In a weft replenishing loom having two shuttles running pick and pick and operating on a cycle of eight picks each of which starts when the lay is on top center, a magazine at one end of the loom having two groups of reserve bobbins for replenishment of the shuttles, one group for each shuttle, electric weft detector means capable of giving indication of exhaustion of weft in one shuttle on the first pick and in the other shuttle on the sixth pick of said cycle, an electric holding contact closed when the detector gives indication of weft exhaustion and remaining closed after said indication, a second electric contact normally open, pattern chain mechanism closing said second contact before the lay reaches the bottom center position thereof on the next pick following any pick on which said weft detector means can indicate weft exhaustion, a solenoid normally de-energized, operating means having an operating movement each pick of the loom, electric circuit means including said contacts and solenoid in series effective to energize the solenoid when both contacts are closed, weft replenishing mechanism including a part movable from the normal position thereof to transfer position preparatory to replenishment of weft in either shuttle by the replenishing mechanism, and means controlled by said solenoid causing the operating means to move said part of the replenishing mechanism to transfer position incident to energization of said solenoid.

17. In a weft replenishing loom having two shuttles running pick and pick and operating on a cycle of eight picks each of which starts when the lay is on top center, the loom having a magazine at one end thereof provided with two groups of reserve bobbins for replenishment of the shuttles, one group for each shuttle, a transfer latch for the magazine normally in non-transfer position but movable to transfer position preparatory to replenishment of either shuttle, an operating member for the latch, vibrator lever means effective when down to cause the operating member to be in the normal non-transfer position thereof but effective when raised to cause the operating member to move to the operating position thereof to move the latch to transfer position, electric weft detecting means capable of indicating weft exhaustion in one shuttle on the first pick and in the other shuttle on the sixth pick of said cycle, an electric holding contact closed upon indication of weft exhaustion by said detector means on either the first or sixth pick of said cycle and remaining closed subsequent to said indication, a second electric contact normally open, pattern chain mechanism closing the second contact prior to bottom center position of the lay on the pick next following a pick on which indication is given and effecting opening of said second contact on the second pick after said indication, a solenoid effective when energized to raise said vibrator lever means, an electric circuit means including said contacts and solenoid in series energizing the solenoid upon closure of the second contact

65

70

75

subsequent to closure of the holding contact, opening of said second contact on said second pick effecting deenergization of the solenoid, whereupon the vibrator lever means moves to normal position and said operating member returns from the operating position to the non-transfer position thereof, and means effective to open said holding contact incident to said return movement of the operating member to the non-transfer position thereof.

18. In a weft replenishing loom having two shuttles running pick and pick and operating on a cycle of eight picks each of which starts when the lay is on top center, one shuttle being inactive on the first pick and the other shuttle being inactive on the sixth pick of said cycle, the loom having a magazine provided with two groups of reserve bobbins for replenishment of the shuttles, electric weft detecting means capable of indicating weft exhaustion in said one shuttle on the first pick and in said other shuttle on the sixth pick of said cycle, an electric holding contact closing when either shuttle is inactive in the event of indication of weft exhaustion by the detector means and remaining closed subsequent to said indication, a second electric contact normally open but closing on the pick next following any pick on which indication of weft exhaustion occurs, and control means for the magazine causing the latter to effect replenishment of either shuttle on the next pick subsequent to indication of weft exhaustion in the shuttle when the latter is inactive by a corresponding bobbin drawn from the magazine incident to closure of the second contact if the first contact is closed.

19. In a weft replenishing loom having two shuttles running pick and pick and operating on a cycle of eight picks each of which starts when the lay is on top center, one shuttle being inactive on certain picks of the cycle including the first and third picks and the other shuttle being inactive on certain picks of the cycle including the sixth and eighth picks, the loom having a magazine provided with two groups of reserve bobbins for replenishment of the shuttles, one group for each shuttle, an electric holding contact capable of closing on either the first or sixth pick of said cycle when said one or said other shuttle is inactive in the event of indication of weft exhaustion in the shuttle and remaining closed during the next pick of the loom, a second electric contact normally open but closing before the lay reaches bottom center on the second and seventh picks of said cycle, and control means for the magazine causing the latter to effect replenishment of said one shuttle on the third pick and of said other shuttle on the eighth pick of the cycle, provided indication of weft exhaustion has been given by the shuttles, by bobbins drawn from the corresponding groups of bobbins in the magazine incident to closure of the second contact if the first contact is closed.
